(57) CLAIM

The ornamental design for an outdoor box, as shown and described.

DESCRIPTION

FIG. 1 is a front, right, top perspective view of an outdoor box showing my new design;

FIG. 2 is a back, left, bottom perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is an enlarged view of the encircled area 9 of FIG. 1;

FIG. 10 is an enlarged view of the encircled area 10 of FIG. 2; and,

FIG. 11 is an enlarged view of the encircled area 11 of FIG. 8.

The broken lines in the figures illustrate portions of the outdoor box that form no part of the claimed design.

1 Claim, 11 Drawing Sheets
